UNITED STATES PATENT OFFICE.

NORTON W. KINNEY, OF HAVERHILL, MASSACHUSETTS, ASSIGNOR TO SLIPPER CITY WOOD HEEL COMPANY, OF HAVERHILL, MASSACHUSETTS, A CORPORATION OF MASSACHUSETTS.

WOOD-HEEL-GROOVING MACHINE.

Application filed May 31, 1928. Serial No. 642,529.

This invention relates to automatic machinery and is herein disclosed in connection with a machine for automatically grooving wood heels.

5 By grooving wood heels is meant the cutting of the breast curve in the front portions of the heels. This operation takes place immediately after the sawing of the rough block, and before the turning of the lateral 10 curved surface.

The grooving operation has heretofore been performed by placing the blank in a holder and traversing the holder by hand over a cutter arranged to form the proper 15 curve. It has been proposed to perform the operation automatically by feeding the blanks on to a carrier by which they are carried past the cutter, but considerable difficulty has been experienced in such machines 20 in gaging the blank on the carrier and in supporting it against the pressure of the tools.

It is therefore a primary object of the 25 present invention to provide a jacking or holding instrumentality operating in connection with a carrier to support the blanks positively and effectively against the tool pressure. Advantageously the blank is automatically gaged on the carrier in proper relation to the tools before it is engaged by the 30 jack, and still another important feature of the invention consists in the arrangement of the jacking instrumentality to grasp and release the blank without disturbance of 35 its already gaged position. As exemplified in the embodiment shown, the jack is arranged to have rolling contact with the work and, as illustrated, the jack is formed as a resilient-toothed wheel which rolls on to the 40 blank as the blank is carried under it, the teeth engaging previously formed scores in the blank. The forces applied to the blank during jacking and unjacking are thus varied slowly and disturbance of the blank on 45 the carrier is avoided.

The rolling jacking and unjacking action above described is advantageous from another point of view. There is, as will be seen, more than one tool necessary to effect 50 the proper grooving operation, and it has been found that a device which holds the blank jacked continuously while passing all the tools gives trouble in operation: if it is to move with the blank, it must be mechani-

cally complicated and if it does not move 55 with the blank much friction is generated. By the present invention, the blank is jacked only when in engagement with a tool, and as stated, the jacking and unjacking are done so gradually as not to disturb the gaged position of the blank on the carrier.

56 The invention also provides an improved device for removing finished work from the machine, a feature of which is an adjustment to follow gaging movements of the carrier in 60 order to preserve the operative relation between them.

These and other features of the invention comprising certain combinations and arrangements of parts will be understood from 70 the following description of a preferred embodiment thereof selected for purposes of illustration and shown in the accompanying drawings in which,

Fig. 1 is a front elevation of the machine; 75

Fig. 2 is a plan view;

Fig. 3 is a section on the line 3—3 of 80 Fig. 1;

Fig. 4 is a detail of the conveyor;

Fig. 5 illustrates the blank and the product cut from it;

Fig. 6 is a perspective view of a portion of the mechanism; and

Fig. 7 is a perspective view of one link of 85 the conveyor.

The main frame 10 of the machine carries detachable brackets 12 and 14 in which are mounted in any convenient manner electric motors 16, 17 with vertical spindles 18, 19 carrying at their upper ends the finishing 90 and roughing cutters 20 and 22, respectively. The spindles of these motors, as shown, are in a vertical plane parallel to an endless belt carrier 24 which is traversed past them in the direction of the arrow in 95 Fig. 1 over the sprocket wheels 26, 28, which are driven in any appropriate manner. A third shaft 30 having a wobble-saw 32 at its upper end is driven by a direct connected motor 34, the whole construction being pivoted at 36 in the bottom of the main frame 100 to permit adjustment. The upper end of the shaft has bearings in a plate 38 mounted to slide in a guide 40 on the frame 10 and adjustable therein by means of a screw 42 and bolts 44. This adjustment moves the saw toward and from the endless belt carrier about the pivot 36 in order to gage 105

the cut of the saw in the work. The plate 38 has a guide 46 in which slides another plate 48 adjustable by screw and bolts as shown in Fig. 6 and carrying a gage 50 which is thus adjustable toward and from the endless belt carrier 24. The adjustment of the saw regulates the gage point of the saw cut with regard to the cutters 20 and 22 and the gage 50 adjusts the position of the work with regard to the combined tool system.

The carrier 24 is composed of links 52 (see Fig. 7) which carry upstanding partition members 54. The distance between the partitions is not equal to the length of the links as shown. The reason for this is that the partitions should of course be spaced as closely together as possible having regard to the thickness of the work pieces placed between them, whereas the links may under certain conditions need a somewhat greater length in order to secure the requisite stability under the pressure of the jacks. In the machine shown, there are four compartments to every three links and the partitions 54 are spaced accordingly. The links are hinged together in any convenient manner and each carries a pair of dogs 56 screwed to it. These dogs each have two sharp upwardly projecting teeth as shown in Fig. 7, and serve to steady the work under the pressure of the tools and the jacks and specially in passing from one jack to the other as will be seen.

The endless belt carrier 24 runs upon a flat plate or track 58 (see Figs. 3 and 4). This plate rests on two downwardly projecting wedges 60 which co-operate with two upwardly facing wedges 62 which slide in guides upon brackets 64 suspended opposite the two cutter shafts. These wedges can be adjusted in or out by screws 66 thereby adjusting the height of the plate 58 and consequently of the endless belt carrier 24. It will be seen in Fig. 4 that the right hand end of this plate as here constructed is bolted into the frame of the machine and is not therefore vertically adjustable. This simplifies the drive of the chain somewhat and inasmuch as the cutter 22 is only a roughing cutter and no great accuracy in its cut is required, vertical adjustment of the endless belt carrier in its neighborhood need be only reasonably accurate. The total adjustment of the plate 58 in the vicinity of the finishing cutter 20 is considerably less than half an inch and it has been found in practice that the device as constructed works quite satisfactorily.

The wood heel blocks 68 are placed on the carrier as shown at the right hand side of Fig. 1. As they are carried along they strike a guide 70 pivoted at 72 on a standard 74 mounted on the frame of the machine. This guide 70 can swing horizontally

between the fingers of a guide 76 which steady it vertically and is pushed toward the saw and cutters by a spring 78. This guide 70 has a beveled front edge 80 which contacts with the rear surfaces of the work blocks 68 and forces them forward against the gage 50 as they pass it. Vertically adjustable in the frame 74 by a screw 82 is a slide 84 carrying an arm 86 which overhangs and exerts spring pressure upon a holding member 88 by means of springs 90. This holding member is hung upon the end of an arm 92 pivoted at 94 on the slide 84 and is guided in its vertical movement by plates 96 and 98 bolted to the arm 86. The under side of this member is scored parallel to its length and forms corresponding scores in the tops of the blocks 68 as they are carried along under it. As the blocks pass under the member 88 they are forced down firmly upon the dogs 56 which bite deeply enough to steady them in position upon the endless belt carrier until they are knocked off at the end of the operation. The pressure of the member 88 also supports the blocks during the cut of the saw 32 which trims the lip of the heel at 100 as shown in Figs. 5 and 6.

The vertical extent of the arc of this saw is of no particular consequence, since, as shown in Fig. 5, the upper part of the kerf is cut out by the grooving cutters. The carrier 24 is rabbeted as shown at 101. This permits the blanks 68 to overhang, as shown in Fig. 6, and allows the saw to cut a clean bottom edge on the blank.

The blocks are supported under the considerably stronger pressure of the roughing and finishing cutters by jacks in the form of rotating idler wheels 102 and 104 respectively. These are mounted upon horizontal axes 103 extending crosswise of the endless belt carrier in frames 106, 108, which are vertically adjustable by means of screws 110, 112 in slides 114, in frames 116 which are adjustable in turn toward and from the endless belt carrier by screws 118 as shown in Fig. 2. The frames 116 are clamped in position by clamp screws 120. The jack wheels 102, 104 are provided with spring pressed teeth 122 as shown in Fig. 3, the springs being strong enough to exert sufficient pressure to hold the work blocks 68 firmly against the endless belt carrier under the pressure of the cutters 20 and 22. These teeth as shown in Fig. 3 are scored, the scores matching the ridges already cut in the blocks by the shoe 88. The centers of the jack wheels are arranged somewhat in advance of the centers of the cutter shafts because the cut ends at the instant that the edge of the block passes the center of the cutter shaft and begins considerably before the advanced edge of the block reaches the center of the cutter shaft. The jacks are

arranged to correspond approximately to the centers of the cutting strokes of the cutter teeth. After passing the first cutter shaft the blocks pass to the second jack wheel 104 without the exercise of any downward pressure upon them. The pins 56 hold them from accidental displacement on the endless belt carrier and they pass under the jack wheel 104 without disturbance.

10 The teeth of these jack wheels are spaced sufficiently close together so that at least one of them will certainly strike a work block in any position upon the endless belt carrier and they are set so low in the slides 15 that a substantial compression of the springs is effected so that the work blocks are held very firmly.

It will be observed that the large diameters of the idler wheels as compared with the dimensions of the wood heel blocks give them a long arc of contact with the blocks and enable them to hold the blocks firmly during the entire time that the cutters are operating on them.

25 After passing the second cutter which is arranged to remove perhaps one-eighth inch of stock, the work blocks pass out to the left in Fig. 1 and are removed from the carrier by an arm 124. This arm is pivoted upon a horizontal pivot 126 in a block 128 having a cylindrical portion 130 mounted for vertical movement in a plate 132 and held by a set screw 134 which engages a peripheral notch in the cylindrical portion 130, the notch being of considerably greater width than the thickness of the screw so that the cylindrical portion 130 can move up and down in its hole in the plate 132. A pin 136 is mounted upon the left hand end of the 30 plate 58, and supports the rear end of the member 124. This pin is of such length that as the plate 58 is adjusted up and down, it will raise the rear end of the member 124 to a sufficient height to permit the passage 35 of the partitions 54 under it, this vertical adjustment of the member 124 being permitted by movement of the stud 130 in its hole. The finished work blocks as they come off at the left strike the slanting edge 138 40 of the member 124 and are pushed off the carrier into a conveniently situated barrel.

The partitions 54 will always be of such height as to permit the upward projection of any work block beyond their tops. In 45 case any work block passes under the member 124 for any reason, the member 124 can tilt upwardly around the end of the pin 136 and the block will be carried around to its outer end 140 and drop on the floor. This 50 upward movement is steadied by the engagement of a fin 142 mounted upon the member 124 with a correspondingly upwardly extending fin 144 on the member 132, a pin and slot guide at 146 being provided. A 55 spring 148 extending between the block 128

and the member 132 holds the member 124 in its lowermost position in contact with the upper ends of the partitions 54. The member 132 is pivoted at 150 to permit horizontal movement upon the table 152 upon 60 which it rests. This movement is guided by a pin and slot arrangement at 154 and the member 132 is held in the position shown in Fig. 2 by a spring 156. Thus in case a block becomes jammed against the face 138 in some 65 way both plates 138 and 132 will swing toward the bottom of Fig. 2 around the pivot 150, allowing the block to be carried over the wheel 126 and dropped upon the 70 floor.

75 In operation, the attendant puts the blocks 20 into the pockets on the links as rapidly as they come up on the wheel 28. They are carried against the arm 70 and pressed against the gage 50. They then pass under the holding member 88 which scores their tops and holds them against the pressure of the saw 32 which trims off the lip at the breast. They then pass from under the 80 member 88, under the jack wheel 102 which has been suitably adjusted in vertical and horizontal directions and which holds them firmly against the pressure of the roughing cutter 22. They then pass from under this 85 wheel and shoe across to the similarly adjusted wheel 104 which holds them likewise against the pressure of the finishing cutter 20, after which they pass to the knock-off 90 arm 124 and fall into the receptacle arranged to receive them.

95 Having described my invention, what I claim as new and desire to secure by Letters Patent of the United States is:—

1. In a machine of the class described, a 100 carrier, a tool adjacent to the path of movement of the carrier, and a rolling disk-shaped holding member having resilient teeth, constructed and arranged to engage corresponding indentations in a work piece and to hold the work piece on the carrier firmly in operative relation to the tool, the 105 diameter of the disk being large as compared with the tool-treated dimensions of the work piece.

110 2. In a machine of the class described, a carrier, a tool adjacent to the path of movement of the carrier, and a rolling disk-shaped holding member, having resilient teeth, constructed and arranged to turn on an axis perpendicular to the line of travel 115 of the carrier and to hold a scored heel blank on the carrier firmly in operative relation to the tool, by engagement of the teeth with the scores in the heel blank, the diameter of the disk being large as compared with the tool-treated dimension of the work piece.

120 3. In a wood heel block making machine, a carrier having partitions arranged to hold wood heel blocks 125 between them, and to carry them past the 130

- tool, and a knock-off member for removing finished work from the carrier arranged to ride on the tops of the partitions and to engage the projecting portions of the heel blocks.
4. In a machine of the class described, a carrier having partitions arranged to hold work pieces between them, and a knock-off member for removing finished work from the carrier arranged to contact with and to push the work laterally from the carrier, and to ride freely on a work piece which becomes accidentally carried under it until such piece has been carried out of the machine.
5. In a machine of the class described, a carrier having partitions arranged to hold work pieces between them, and a knock-off member for removing finished work from the carrier arranged to contact with and to push the work laterally from the carrier, and to yield laterally in case a work piece accidentally refuses to slide from the carrier, until such piece has passed out of the machine.
6. In a machine of the class described, a work carrier and a knock-off mechanism for removing finished work from the carrier comprising a vertically moving member and a horizontally moving member arranged to yield resiliently in the directions indicated, to release a work piece which has been accidentally held on the carrier.
7. In a machine of the class described, a work carrier and a knock-off mechanism for removing finished work from the carrier comprising a vertically moving member and a horizontally moving member arranged to yield resiliently in the directions indicated,
- to release a work piece which has been accidentally held on the carrier, one of said members being carried by the other.
8. In a machine of the class described, a tool, a carrier having partitions arranged to receive work pieces between the partitions and carry them past the tool, the carrier being adjustable transversely of its surface to gage the tool-cut in the work, and a knock-off member for removing finished work from the carrier, arranged to ride on the tops of the partitions, irrespective of the carrier adjustment.
9. In a machine of the class described, a tool, a carrier having partitions arranged to receive work pieces between the partitions and carry them past the tool, the carrier being adjustable transversely of its surface to gage the tool-cut in the work, and a knock-off member for removing finished work from the carrier supported loosely on the main frame of the machine and arranged to have a fixed relation to the tops of the partitions irrespective of the adjustment.
10. In a machine of the class described, a tool, a carrier having partitions arranged to receive work pieces between the partitions and carry them past the tool, a support on which the carrier moves, adjustable transversely of its surface to gage the tool-cut in the work, and a knock-off member for removing finished work from the carrier supported by said support in fixed relation to the tops of the partitions.

In testimony whereof I have signed my name to this specification.

NORTON W. KINNEY.
